Shoemaker-Merrill Company

Application March 13, 1939, Serial No. 261,499

4 Claims. (Cl. 74—70)

This invention relates to a fan oscillating reduction mechanism and has for its primary object to provide improved means operable by the motor of an electric fan for slowly oscillating the fan about an axis extending at an angle to the axis of rotation thereof.

The conventional electric fan rotates at a comparatively high rate of speed, say for example approximately 300 R. P. M., whereas the numbers of oscillations is considerably less, usually of the order of 8 per minute. With the motor of the fan supplying power for operating the oscillating mechanism, reduction means having an extremely high reduction ratio is required and the means for this purpose heretofore employed have been inefficient.

Accordingly, it is an important object of this invention to provide a fan oscillating reduction mechanism incorporating a higher degree of efficiency than has heretofore been attainable.

It is important, of course, to provide for air circulation through the motor housing, to avoid overheating of the motor. In the case of an oscillating fan, however, the gear reduction for the oscillating mechanism is ordinarily attached to the rear face of the motor housing, and due to the great number of gear trains necessary to obtain the required reduction the reduction gearing and its housing is comparatively large and covers a large area of the housing which otherwise could be ventilated. An important object of this invention is to provide reduction gearing of very compact nature in order that it will offer no material obstruction to circulation of air through the motor housing.

Another object is to provide a fan oscillating reduction mechanism consisting of comparatively few, light-weight parts, to thereby avoid adding unnecessary weight to the load required to be oscillated.

Another object is to provide a fan oscillating reduction mechanism embodying means for causing the fan to dwell for short periods at different points in its oscillatory movement.

Another object is to provide a fan oscillating reduction means including planetary gearing including an eccentric rotated by the fan motor, two connected pinion gears rotatable on the eccentric, one of said pinions meshing with a stationary reaction gear and the other pinion driving an internal gear which operates the oscillating means. With this arrangement of gearing it is possible to provide a very compact reduction means, and because the number of and area of tooth contact is high the members may be formed

of lighter weight than ordinarily would be the case.

Another object is to provide gearing of the type referred to immediately above embodying a counterweight for counterbalancing the eccentric and pinions and to reduce the rocking couple that is set up by the centrifugal unbalance at high speed.

Other objects and advantages will become more fully apparent as reference is had to the accompanying drawings wherein my invention is illustrated, and in which—

Fig. 1 is an end elevation.

Fig. 2 is a fragmental vertical section taken on the line 2—2 of Fig. 1.

Figs. 3 and 4 are sections taken on the lines 3—3 and 4—4 of Fig. 2.

Fig. 5 is a view looking in the direction of the arrows 5—5, with the housing omitted to expose the parts therebeneath,

Fig. 6 is a vertical section illustrating a modified oscillating reduction means,

Fig. 7 is a view looking in the direction of the arrows 7—7 with the housing omitted to expose the parts therebeneath and,

Fig. 8 is an elevation of a detail.

Referring to Figs. 1 to 5, 1 designates the housing of a motor for an electric fan, the motor (not shown) having a drive shaft 2 extending through the end wall 3 thereof and into a gear housing 4. An extension 5 of reduced diameter, forming a continuation of the drive shaft, is rotatably supported at its outer end in a bearing 6 in a removable cover plate 7 on the housing 4.

Secured upon the shaft extension 5 is an eccentric 8 and a pair of connected pinion gears 6 and 10 are rotatably supported by anti-friction bearings 11 on the eccentric 8. The gear 9 meshes with a stationary internal gear 12, and the gear 10 meshes with an internal gear 13 which is rotatably mounted upon the shaft extension 5 and also rotatably supported by an anti-friction bearing 14 in the housing 4.

It will be noted, at this stage of the description, that the eccentric 8 in revolving the gear 9 about the fixed internal gear 12 causes rotation of the gear 9 relative to the eccentric. The gear 10, being connected to the gear 9, likewise rotates relative to the eccentric as it revolves about the axis of rotation of the eccentric. The internal gear 13 is rotated by the gear 10 at a speed much less than the speed of rotation of the eccentric.

A counterweight 15 is secured to the shaft extension 5 and has a portion 16 extending between the gears 9—10 and 12—13 for counter-

balancing the eccentric and reducing the rocking couple set up by centrifugal unbalance at high speed.

Mounted on the stem portion 17 of the internal gear 13 is a helical gear 18 which meshes with a similar helical gear 19 on a vertical shaft 20. On the lower end of the shaft 20 is a disc 21 having an eccentric pin 22 which is connected by a connecting rod 23 to a pin 24 on the stationary motor base 25. The motor housing 1 is supported at 26 on the base 25 for rotation about a vertical axis, and as the pin 21 is revolved about the shaft 20 it co-acts with the connecting rod 23 in oscillating the motor housing on its support 26.

As may be seen in Fig. 1, the housing 4 is comparatively small and does not, therefore, obstruct the ventilating openings 3a in the end wall 3.

In Figs. 6, 7 and 8 the numeral 30 designates an electric motor housing supported upon a stationary base 31 for movement about a vertical trunnion 32. In the housing is an electric motor 33 for operating a shaft 34 upon which is splined an eccentric 35. Rotatably supported by bearings 36 upon the eccentric 34 are two connected gears 37 and 38. The gear 37 meshes with a stationary internal gear 39, and the gear 38 meshes with a rotatable internal gear 40.

As the eccentric 35 rotates the gear 37 is caused to rotate relative to the eccentric because of contact with the stationary gear 39. The gear 38 rotates with the gear 37 and revolves about the axis of the eccentric in a direction opposite to the direction of rotation, and imparts rotation to the internal gear 40 at a speed much slower than the speed of rotation of the shaft 34.

In the stem 41 of the gear 40 is a cam slot 42 and a roller 43, carried by a swinging arm 44, extends into the cam slot. The arm 44 is fixed upon a vertical shaft 45 which has a lever arm 46 on its lower end connected by a connecting rod 47 to a pivot pin 48 on the base 31. As the stem 41 is rotated the arm 44 is oscillated by contact of the roller 43 with the walls of the cam slot, thus oscillating the shaft 45, and through the lever arm 46 and link 47 imparting oscillatory movement to the motor housing.

As may be seen upon reference to Fig. 8 the walls of the cam slot 42 are provided with straight portions 49 which act as dwells. That is, when the straight portions 49 contact the roller 43 oscillatory movement of the motor housing stops for a short interval. Arranged as shown, the dwells in oscillatory movement occur midway between the ends of the reverse oscillating movements. The cam thus constitutes means for intermittently operating the oscillating means.

Although specific embodiments of the invention are shown and described, it will be understood that various changes may be made within the scope of the appended claims without departing from the spirit of the invention, and such changes are contemplated.

What is claimed is:

1. Gearing for converting rotary movement of a drive shaft into oscillatory movement of a second shaft, comprising a cam member loosely mounted on said drive shaft, said cam member having a circumferential cam groove disposed with the main portion thereof in a plane non-perpendicular to the axis of said drive shaft and a relatively short portion disposed in a plane per-

pendicular to the axis of the drive shaft and constituting a dwell, a radial lever on said second shaft having a roller on its free end disposed in said cam groove to oscillate said lever while the roller is in said main portion of said groove and to hold said lever stationary while the roller is in said dwell portion, and speed reducing gearing connecting the drive shaft with said cam member for rotating the cam member at a slower speed than the drive shaft.

2. Gearing for converting rotary movement of a drive shaft into oscillatory movement of a second shaft, comprising a cam member loosely mounted on said drive shaft, said cam member having a circumferential cam groove disposed with the main portion thereof in a plane non-perpendicular to the axis of said drive shaft and a relatively short portion disposed in a plane perpendicular to the axis of the drive shaft and constituting a dwell, a radial lever on said second shaft having a roller on its free end disposed in said cam groove to oscillate said lever while the roller is in said main portion of said groove and to hold said lever stationary while the roller is in said dwell portion, an eccentric mounted on said drive shaft for rotation therewith, a pair of connected planet gears rotatable on said eccentric, a ring gear connected to said cam member and meshing with one of said planet gears, and a stationary ring gear meshing with the other planet gear.

3. Gearing for converting rotary movement of a drive shaft into oscillatory movement of a second shaft, comprising an eccentric secured on said drive shaft for rotation therewith, a pair of connected planet gears rotatable on said eccentric, a stationary ring gear meshing with one of said planet gears, a rotatable ring gear meshing with the other of said planet gears, said rotatable ring gear having an axial pilot stem having a portion formed with a circumferential cam groove, said cam groove being disposed in a plane non-perpendicular to the axis of said stem, and a radial lever on said second shaft having a roller on its free end disposed in said cam groove whereby rotation of the rotatable ring gear causes the walls of the cam groove to oscillate said lever and said second shaft.

4. Gearing for converting rotary movement of a drive shaft into oscillatory movement of a second shaft, comprising an eccentric secured on said drive shaft for rotation therewith, a pair of connected planet gears rotatable on said eccentric, a stationary ring gear meshing with one of said planet gears, a rotatable ring gear meshing with the other of said planet gears, said rotatable ring gear having an axial pilot stem having a portion formed with a circumferential cam groove, the main portion of said cam groove being in a plane non-perpendicular to the axis of said stem and a relatively short portion disposed in a plane perpendicular to the axis of said stem and constituting a dwell, and a radial lever on said second shaft having a roller on its free end disposed in said cam groove whereby rotation of the rotatable ring gear causes the walls of said groove to oscillate said lever while the roller is in said main portion and to hold said lever stationary while said roller is in said dwell portion.
